UNITED STATES PATENT OFFICE.

OSCAR G. PENDLETON, OF DECATUR, ILLINOIS, ASSIGNOR OF ONE-HALF TO HUGH F. ARMSTRONG, OF DECATUR, ILLINOIS.

HYDROCARBON-ENGINE.

1,179,375.

Specification of Letters Patent.

Patented Apr. 11, 1916.

Application filed July 7, 1914. Serial No. 849,606.

To all whom it may concern:

Be it known that I, OSCAR G. PENDLETON, a citizen of the United States, residing at Decatur, in the county of Macon and State 5 of Illinois, have invented new and useful Improvements in Hydrocarbon-Engines, of which the following is a specification.

The invention relates to hydrocarbon engines, and more particularly to the class of 10 combined compressors and engines.

The primary object of the invention is the provision of an engine of this character wherein the compressor is continuously operated to effect the feed of fuel within the 15 explosive chamber, which fuel when exploded constitutes the motive power for the engine, the exhaust from the engine being utilized as motive power to increase the efficiency of said engine without utilizing an 20 excessive amount of fuel in the operation of the same.

Another object of the invention is the provision of an engine of this character wherein the explosive chamber will be automatically 25 cleaned for the removal of carbon therefrom during the working of the said engine.

A further object of the invention is the provision of an engine of this character wherein the fluid utilized for the cleaning of 30 the explosive chamber will be primarily admitted to the jackets of the compressor and engine cylinder for the cooling thereof, and subsequently discharged with the exhaust from the engine.

A still further object of the invention is the provision of an engine of this character which will afford maximum efficiency of driving power without requiring the consumption of a large amount of operating 35 fluid, and also which will work smoothly without vibration, the engine being of novel form to insure reliability and efficiency in its operation.

A still further object of the invention is 40 the provision of an engine of this character which is simple in construction, light in weight, yet strong, durable, and also one which is inexpensive in manufacture and installation.

50 Other objects will be in part obvious and in part hereinafter pointed out.

The invention accordingly consists in the construction, combination of elements and arrangement of parts as will be exemplified in the construction hereinafter set forth, and 55 the scope of the application of which will be indicated in the following claims.

In the drawings:—Figure 1 is a side elevation of an engine constructed in accordance with the invention. Fig. 2 is a similar 60 view, looking toward the opposite side of the engine. Fig. 3 is a vertical transverse sectional view on the line 3—3 of Fig. 1. Fig. 4 is an enlarged fragmentary vertical sectional view through the explosive chamber and valve for controlling the admission 65 of explosive fluid to the engine cylinder and the exhaust therefrom. Fig. 5 is a vertical sectional view through the exhaust rotor. Fig. 6 is a detail side elevation of the valve 70 controlling mechanism.

Similar reference characters indicate corresponding parts throughout the several views in the drawings.

Referring to the drawings in detail, A 75 designates a carbureter, B a compressor, C an engine, and D a rotor, which coöperate with each other and constitute the combined compressor and engine, the details of which will be hereinafter fully described. 80

The engine C comprises a piston cylinder 10 formed with a water jacket 11, and within said cylinder is arranged a reciprocating piston 12, the rod 13 of which extends in opposite directions through stuffing boxes 14 85 provided at opposite sides of the cylinder, while above the said cylinder is arranged the compressor B which is of any ordinary well-known construction, and has its piston connected with the rod 13 of the engine piston 12 so that when the engine is working the compressor is active and acted upon directly thereby, the compressor B being mounted upon a support 15 rising from the top of the engine cylinder, while connected 90 with one side of the compressor B is the inlet pipe 16 leading from the carbureter A so that the hydrocarbon fuel will be fed therefrom to the compressor. 95

At one side of the engine cylinder 10 is 100 formed a valve casing 17 having a two-way turning valve 18 rotatably mounted therein,

while above this valve 18 within the said casing 17 is formed an explosive chamber 19, the latter being adapted for communication with the engine cylinder 10 through a passage 20 controlled by the valve 18, and formed in the said casing 17, the valve being also designed to control the exhaust from the engine cylinder 10 through the passage 21 intersected by said valve and formed in the casing 17, the valve being automatically operated in a manner presently described.

Leading from the compressor B to the explosive chamber 19 is a fuel supply pipe 22 in one stretch of which is arranged a cut-off valve rod 23 carrying the valve 24 which controls the communication from the pipe 22 to the explosion chamber 19, and this rod 23 is acted upon by means of a tension spring 25 which normally seats the said valve 24 to close communication between the compressor and the said explosion chamber.

Tapped in one side of the valve casing 17 and projected into the explosion chamber 19 is a spark plug 26, the sparking thereof being controlled in any ordinary well-known manner, and this plug is designed to explode the charges admitted to the explosion chamber 19 from the compressor, which exploded charges are let into the engine cylinder 10 alternately at opposite sides of the piston 12 for reciprocating the same, the charges to the cylinder 10 being controlled by the valve 18 which is automatically operated in a manner presently described.

Supporting the engine cylinder 10 and valve casing 17 is a rotor casing or cylinder 27 in which is arranged a rotor 28 formed in two parts suitably joined together and mounted upon a driven shaft 29 journaled in bearings 30 formed centrally of the rotor cylinder 27, the side walls of the latter being provided with exhaust openings 31 concentrically about the bearings 30 for the exhaust of the spent gases from the engine. The rotor is formed in its two parts with a spirally arranged exhaust course or passage 32 which increases in area from its outer to the innermost end thereof, the inner wider portion of the passage 32 being branched laterally as at 33 to open through opposite sides of the said rotor to permit the exhaust of gas therefrom through the branches 33 and openings 31 to the atmosphere. Formed concentrically about the outermost convolutions of the spiral way or passage 32 and opening through the periphery of the rotor 28 at the center thereof are diagonally disposed pockets or exhaust inlets 34 which communicate with the said way or passage 32 and also communicate with the exhaust passage 21 in the valve casing 17 leading from the cylinder 10 of the engine so that the exhaust fluid entering these pockets 34 in the rotor

28 will cause an impact to drive the rotor in one direction. The exhaust fluid passing through the pockets 34 into the passage 32 expands from the periphery of the rotor to the center thereof prior to its discharge through the openings 31 to the atmosphere, so that the full effect of the exhaust fluid is utilized for impelling the rotor 28 to drive the shaft 29, which may be connected to any part or machinery to be driven.

Mounted on the casing or cylinder 27 for the rotor at one side thereof is a cross head 75 guide 35 in which is slidably fitted a cross head 36, the same being integral with or connected to the rod 13 of the piston 12, and also pivoted to this cross head 36 is one end of a connecting rod 37 which is connected to a crank 38 on the shaft 29 so that power from the engine will be imparted to the said shaft 29 for augmenting the power from the rotor 28, which also drives this shaft.

Arranged upon the base 39 of the rotor 85 casing or cylinder 27, and at one side thereof, is a water pump 40, its piston stem 41 being pivotally connected to a link 42 eccentrically connected to a gear 43 journaled on one side of the cylinder or casing 27, the gear being 90 positioned to mesh with a pinion 44 mounted upon the shaft 29 so that motion from the latter will be imparted to the pump 40 for operating the same, and from this pump extends a water feed pipe 45 which is tapped 95 into the water jacket of the compressor B for the supplying of the same with water during the working of the pump. Mounted in the pipe 45 is a valve casing 46 having therein a three-way valve 47, while leading 100 from this valve casing 46 is a branch pipe 48, so that on regulating the valve 47 the water through the pipe 45 can be directed into the branch 48, and thus be shut off from flowing into the water jacket of the compressor B, as will be clearly apparent, and in this manner it obviates the necessity of stopping the pump 40 during the continued working of the engine.

Leading from the water jacket of the compressor B to the water jacket of the engine cylinder 10 is a pipe 49, so that water can be delivered to the jacket of the engine cylinder 10 for the cooling thereof. Rising from the water jacket of the engine cylinder 10 is 115 a steam exhaust regulator 50, and from the same leads a by-pass pipe 51, the latter opening into the explosion chamber 19 so that when the water is converted into steam by the heat from the engine the same can be 120 admitted to the explosion chamber 19 for the cleaning thereof to free it from carbon or other foreign matter without necessitating the stopping of the engine for this purpose. Arranged in the by-pass pipe 51 is a 125 valve casing 52, the turning valve 53 therein

being provided with an arm 54 to which is connected a controlling rod 55, the same being connected to an oscillating arm 56 pivoted at 57 to the rotor cylinder or casing 27, 5 the arm 56 being also connected to the pivot 58 on the cross head 36 for connecting the rod 37 therewith, it being seen that on the reciprocation of the head the arm 56 will swing, and during its movement the valve 10 53 will be automatically opened and closed for the admission and shutting off of steam to and from the explosion chamber 19 of the engine.

Connected to the stem of the valve plug 15 18 is a toothed sector 59 meshing with a segmental rack arm 60 supported upon a pivot 61 for rocking movement, the pivot being projected from one side of the rotor casing or cylinder 27, and this arm is 20 formed with a fork 62, the limbs of which are engaged by means of a cam 63 carried by the shaft 29 of the rotor so that on the latter becoming active the arm 60 actuates the valve 18 for controlling the intake and 25 exhaust to and from the cylinder 10 of the engine.

Tapped in one side of the pump 40 is a supply pipe 64 which feeds water thereto for the pumping of the same into the jacks 30 sets of the compressor and engine, the heat from the engine being designed to convert the water in the jacket thereof into steam, which is conveyed into the explosion chamber 19 for scavenging the same to free it of 35 carbon or other foreign matter, the converted steam being controlled through the regulator 50 so that an excessive amount of steam can be exhausted to the atmosphere while the engine is active.

40 It will be noted that the exhaust from the engine is utilized for driving the rotor so that the power therefrom will augment the power from the engine for driving energy to be utilized in operating machinery or 45 other purposes.

It will be apparent that the operation of the device is continuous and without any lost motion, and at the same time enabling maximum power to be attained with a minimum consumption of fuel.

From the foregoing description, taken in connection with the accompanying drawings, it is thought that the construction and manner of operation of the device will be 55 clearly apparent, and therefore a more extended explanation has been omitted.

What is claimed is:—

1. The combination with a fluid actuated rotor and a casing therefor, of an engine 60 comprising a cylinder supported upon the casing a reciprocating piston movable in said cylinder and having a stem working through opposite ends thereof, a compressor supported above the cylinder in alinement therewith and having a piston therein connected with one end of the stem, connections between the other end of the stem and the rotor, a valve casing at one side of the cylinder and having an explosion chamber provided with communication with said cylinder and rotor casing, a two-way valve arranged in said valve casing and controlling the communication between the cylinder and the rotor casing, a fuel supply pipe leading from the compressor to the explosion chamber, a spring tensioned valve controlling the communication through said supply pipe, connections between the rotor and the said first-named valve for operating the same, and means for supplying fuel to the compressor.

65 2. The combination with a fluid actuated rotor and a casing therefor, of an engine comprising a cylinder supported upon the casing, a reciprocating piston movable in said cylinder and having a stem working through opposite ends thereof, a compressor supported above the cylinder in alinement therewith and having a piston therein connected with one end of the stem, connections 70 between the other end of the stem and the rotor, a valve casing at one side of the cylinder and having an explosion chamber provided with communication with said cylinder and rotor casing, a two-way valve arranged in said valve casing and controlling the communication between the cylinder and the rotor casing, a fuel supply pipe leading from the compressor to the explosion chamber, a spring tensioned valve controlling the communication through said supply pipe, connections between the rotor and the said first-named valve for operating the same, and means for supplying fuel to the compressor.

75 3. The combination with a fluid actuated rotor and a casing therefor, of an engine comprising a cylinder supported upon the casing, a reciprocating piston movable in said cylinder and having a stem working through opposite ends thereof, a compressor supported above the cylinder in alinement therewith and having a piston therein connected with one end of the stem, connections 80 between the other end of the stem and the rotor, a valve casing at one side of the cylinder and having an explosion chamber provided with communication with said cylinder and rotor casing, a two-way valve arranged in said valve casing and controlling the communication between the cylinder and the rotor casing, a fuel supply pipe leading from the compressor to the explosion chamber, a spring tensioned valve controlling the communication through said supply pipe, connections between the rotor and the said first-named valve for operating the same, and means for supplying fuel to the compressor.

85 4. The combination with a fluid actuated rotor and a casing therefor, of an engine comprising a cylinder supported upon the casing, a reciprocating piston movable in said cylinder and having a stem working through opposite ends thereof, a compressor supported above the cylinder in alinement therewith and having a piston therein connected with one end of the stem, connections 90 between the other end of the stem and the rotor, a valve casing at one side of the cylinder and having an explosion chamber provided with communication with said cylinder and rotor casing, a two-way valve arranged in said valve casing and controlling the communication between the cylinder and the rotor casing, a fuel supply pipe leading from the compressor to the explosion chamber, a spring tensioned valve controlling the communication through said supply pipe, connections between the rotor and the said first-named valve for operating the same, and means for supplying fuel to the compressor.

95 5. The combination with a fluid actuated rotor and a casing therefor, of an engine comprising a cylinder supported upon the casing, a reciprocating piston movable in said cylinder and having a stem working through opposite ends thereof, a compressor supported above the cylinder in alinement therewith and having a piston therein connected with one end of the stem, connections 100 between the other end of the stem and the rotor, a valve casing at one side of the cylinder and having an explosion chamber provided with communication with said cylinder and rotor casing, a two-way valve arranged in said valve casing and controlling the communication between the cylinder and the rotor casing, a fuel supply pipe leading from the compressor to the explosion chamber, a spring tensioned valve controlling the communication through said supply pipe, connections between the rotor and the said first-named valve for operating the same, and means for supplying fuel to the compressor.

105 6. The combination with a fluid actuated rotor and a casing therefor, of an engine comprising a cylinder supported upon the casing, a reciprocating piston movable in said cylinder and having a stem working through opposite ends thereof, a compressor supported above the cylinder in alinement therewith and having a piston therein connected with one end of the stem, connections 110 between the other end of the stem and the rotor, a valve casing at one side of the cylinder and having an explosion chamber provided with communication with said cylinder and rotor casing, a two-way valve arranged in said valve casing and controlling the communication between the cylinder and the rotor casing, a fuel supply pipe leading from the compressor to the explosion chamber, a spring tensioned valve controlling the communication through said supply pipe,

connections between the rotor and the said
first-named valve for operating the same,
means for supplying fuel to the compressor,
means for exploding the charges within the
explosion chamber, and a guide for the ro-
tor casing for the stem of the piston work-
ing within the engine cylinder.

In testimony whereof I affix my signature
in presence of two witnesses.
